UNITED STATES PATENT OFFICE.

HENRY A. CHRISTY, OF KENILWORTH, ILLINOIS.

RAIL-JOINT.

976,985.

Specification of Letters Patent. Patented Nov. 29, 1910.

Application filed August 4, 1910. Serial No. 575,536.

To all whom it may concern:

Be it known that I, HENRY A. CHRISTY, a citizen of the United States, residing at Kenilworth, in the county of Cook and State 5 of Illinois, have invented certain new and useful Improvements in Rail-Joints, of which the following is a specification.

It has heretofore been considered advisable, if not quite necessary, to make the 10 joints of railway tracks as rigid and firm as circumstances might permit, the theory being that such rigidity of connection was necessary to maintain the proper alinement of the rails and to secure the most advanta- 15 geous conditions for the traffic over the rails and the preservation of the latter in the best condition. Consequently it has been customary and usual heretofore either to place the rail joints above a tie or between rail- 20 road ties, but in any case the fish plates or clamping members have ordinarily been sup- ported by the ties proper to secure a proper foundation and support for the joint. In 25 some cases concrete or other solid piers have been built beneath the joints to hold the same rigidly and fixedly in position. The use of concrete or other similar hard road- beds has also been considered. I have dis- 30 covered, however, that these practices are not such as to secure the best conditions in service and consequently it is one of the leading aims and objects of this invention to preserve as much as possible the natural elasticity and flexibility of the rails so that 35 the shocks and jars of the trains passing over the same, and particularly over the joints, may be absorbed and dissipated by the resiliency of the rails themselves. Con-sequently, in accordance with the principles 40 of this invention, I make the fish plates or clamping members relatively short and dis- pose the rail joints between the ties or sleepers and do not directly support the clamps on these ties or any other compara- 45 tively rigid members. Considerable atten- tion has heretofore been paid to the support of the rail heads at the joints and not in- frequently have means been provided to sup- port the overhanging portions of the heads 50 over the base flanges of the rail. I consider this practice entirely unnecessary and un- desirable and in my improved means for maintaining the rails in line, I support the ends by clamping members projecting be- 55 beneath the rails, such bottom portions or parts of the clamps having sufficient body

to act as the supporting means for the rail ends thus thereby preventing any substantial vertical movement of the rails relatively to one another. These clamp members also 60 have side portions disposed on opposite sides of the webs of the rails which act to maintain the horizontal alinement of the rails. The clamping members in addition prefer- 65 ably have a wedge connection with the bases of the rails and are supplied with wooden or other fillers between their upstanding portions and webs of the rails, the clamps being held in operative position by means of a suitable number of bolts passed there- 70 through. These clamping or securing mem- bers are out of contact with the heads of the rails and with the edged portions of the rail bases. These and other advantages of 75 my invention will be more apparent by ref- erence to the accompanying drawings which show preferred embodiments of my im- provements, and in which,

Figure 1 is a side elevation showing the rail joint applied to the ends of two adjacent 80 rails; Fig. 2 is a transverse vertical section on the line 2—2 of Fig. 1; Fig. 3 is a view similar to Fig. 1, but showing a modified form of rail joint; Fig. 4 is a vertical trans- 85 verse section on the line 4—4 of Fig. 3; and Fig. 5 is a reduced side elevation showing the rail joint in connection with the ends of the adjacent rails and occupying a position between adjacent ties.

The adjacent rails 10, 10 are provided as 90 is usual, with the heads 11, 11 and the flanges 12, 12. In the preferred form of my rail joint a metallic plate 13 is placed be- 95 neath the flanges 12, 12 of adjacent rails. Applied to the sides of the webs of adjacent 100 rails 10, 10 are the oppositely disposed clamping members 14, 14, each of which has an upstanding portion 15, and a base por- 105 tion 16, which projects beneath the flanges 12, 12 of the adjacent rails and occupies a position just below the plate 13. Inserted between the upstanding portions 15, 15 of the clamping members and the webs of the rails 10, 10 are the fillers 17, 17 which are preferably made of wood or some similar 110 compressible material.

The upstanding portions 15, 15 of the clamping members are connected with each other by means of the bolts 18, provided with the nuts 18^a, which pass through the 110 fillers 17 and suitable apertures in the webs of the adjacent rails 10, 10. The base por-

tions 16 of the clamping members are also connected by means of the bolts 19, provided with the nuts 19^a. It will be noticed that the base portions 16 of the clamping members are of substantial thickness in order to provide adequate support for the ends of the adjacent rails 10, 10.

As best shown in Fig. 5, the clamping members 14 are applied to the ends of the rails between adjacent ties 20, thus forming a rail joint with no rigid support directly below it.

Each of the clamping members 14 engages the upper portion of the flange 12 of each rail and is so formed that vacant spaces 21 occur between the edges of the flanges 12 and the clamping members. It will, therefore, be apparent that on tightening the nuts 18^a and 19^a used in connection with the bolts 18 and 19, the clamping members will be drawn together exerting a wedging action on the flanges of the rails. The plate 13 beneath these flanges is for the purpose of enabling the bend in each clamping member to be of greater height inasmuch as the process of forming the clamps is greatly facilitated thereby.

It will be noted that the upper ends of the upstanding portions 15 of the clamps do not come in contact with the lower surface of the heads 11 of the rails. I have found that such contact and the supporting connection which is ordinarily furnished by the fish plate is entirely unnecessary, and I therefore, confine the clamping connection between the adjacent ends of the rails to the flanges and webs of the same.

In Figs. 3 and 4 I have illustrated a form of clamping member which is similar to that described in connection with Figs. 1 and 2 except that no plate 13 is used beneath the flanges of the rails. As explained above, I prefer to use the modification of my invention which is described in connection with Figs. 1 and 2, but I can readily use the modification shown in Figs. 3 and 4 if for any reason such a construction is considered more advisable.

It will be apparent from the foregoing description that the two adjacent rails are connected in such manner that the resiliency which is found between ties is retained at the joints. This is a great advantage inasmuch as the ends of the rails bend in unison and the car wheels have no opportunity of striking the end of one rail on leaving the adjacent rail which is depressed by the weight of the car.

It will be clear to those skilled in the art that considerable departure could be made from the exact structure which I have de-

scribed without departing from the spirit of my invention.

What I claim is:

1. In a rail joint, the combination of a pair of clamping members adapted for wedging engagement with the base flanges of the ends of adjacent rails, said members having upstanding portions on opposite sides of the rail webs, and means to fasten said members together, said members being out of contact with the heads and webs of the rails and the edge portions of the base flanges, substantially as described.

2. In a rail joint, the combination of a pair of clamping members adapted for wedging engagement with the base flanges of the ends of the adjacent rails, the portions of said members below said base flanges being of substantial thickness, said members having upstanding portions upon opposite sides of the rail webs, and means cooperating with the portions of said members below said base flanges adapted to clamp said members together, said members being out of contact with the heads and webs of the rails and the edge portions of the base flanges.

3. In a rail joint, the combination of a pair of clamping members adapted for wedging engagement with the base flanges of the ends of adjacent rails, said members having upstanding portions on opposite sides of the rail webs, compressible fillers between said upstanding portions and the opposite sides of the rail webs, and means to fasten said members together, said members being out of contact with the heads and webs of the rails and the edge portions of the base flanges.

4. In a rail joint, the combination of a pair of clamping members adapted for wedging engagement with the base flanges of the ends of adjacent rails, said members having horizontal rail-supporting portions of substantial thickness adapted to be disposed beneath the base flanges of the rails, said members having upstanding portions on opposite sides of the rail webs, bolts extended through apertures in the horizontal supporting portions of said members and adapted to clamp the members together, and additional bolts extended through apertures of the rail webs and upstanding portions adapted to assist in clamping said members together, said members being out of contact with the heads and webs of the rails and the edge portions of the base flanges.

HENRY A. CHRISTY.
